UNITED STATES PATENT OFFICE.

JEROME J. RUEDIGER, OF BALTIMORE, MARYLAND.

SANITARY MILK-BOTTLE LOCK.

1,414,584.

Specification of Letters Patent. Patented May 2, 1922.

Application filed November 3, 1921. Serial No. 512,531.

To all whom it may concern:

Be it known that I, JEROME J. RUEDIGER, a citizen of the United States, residing at Baltimore city, in the State of Maryland, 5 have invented certain new and useful Improvements in Sanitary Milk-Bottle Locks; and I do declare the following to be a full, clear, and exact description of the invention, such as will enable others skilled in 10 the art to which it appertains to make and use the same.

This invention relates to an improved sanitary milk bottle lock and it has for its principal object to generally improve upon 15 and simplify devices of this class by producing one which is practical, one with which the milk bottle can be easily and quickly engaged or disengaged, and one which is comparatively inexpensive to both 20 the manufacturer and the user.

Another object of the invention is to provide a milk bottle lock which is such in construction that it constitutes a cover for the open end of the bottle and prevents entrance 25 of dirt and other extraneous matter. It will be recalled that during cold weather, the contents of the bottle often freezes, expands, and forces the cap off and permits the entrance of dirt. However, by using the 30 improved lock, such circumstances are overcome.

Another object of the invention is to provide a milk bottle lock which embodies stationary and movable hinged members for 35 gripping the neck of the bottle, together with novel means for holding these members together to prevent unauthorized persons from disengaging the bottle from the device, the construction of the parts being 40 such that the device can be placed on a door frame and adjacent the door so that the part in which the locking means is located, will be arranged in abutting relation with the door and will be rendered inaccessible 45 when the door is closed.

A further object of the invention is to provide a device of this class embodying the aforesaid bottle engaging members together with novel locking means for said members, 50 which means is ineffective until the bottle is placed in position and is then rendered automatically effective to hold the members against separation.

A still further object of the invention is 55 to provide a milk bottle lock which includes

an attaching plate of less length than the bottle-engaging body or means, whereby when the fastening screws are passed through the attaching plate and anchored in the stationary support, the ends of the 60 body will act to prevent persons from using screw drivers or the like for removing the device bodily from the support.

It is another object of the invention to provide bottle locking devices of this class 65 which are such in construction that a number of them can be placed alongside of one another and in abutting relation, as will be hereinafter better described, whereby each device serves to render the locking means 70 of the other adjacent device inaccessible.

Other objects and advantages of the invention will be apparent during the course of the following description.

In the accompanying drawings forming a 75 part of this specification and in which like numerals are employed to designate like parts throughout the same:

Figure 1 is a horizontal sectional view through a portion of a door frame and door 80 showing the bottle lock associated therewith.

Figure 2 is a side elevational view with the door swung away from the lock and one of the hinged sections of the latter swung up to indicate the manner in which the bottle is disengaged.

Figure 3 is a front elevational view with the movable section swung up to disclose the construction more clearly.

Figures 4 and 5 are sectional views taken 90 substantially on the planes of the lines 4-4 and 5-5 respectively of Figs. 1 and 2 respectively.

Figure 6 is a top plan view showing the manner of employing two or more of the 95 bottle locks and showing how each one co-acts with the other.

As previously indicated, the improved bottle lock is intended to be installed on a stationary part of the house adjacent a window or a door so that the latter will co-act therewith to render the locking means inaccessible so long as the closure is closed. This feature of the invention will be set forth more clearly as the description goes on. Although, the device can be just as effectively used in connection with a window, I have shown it associated with a door D which is hinged to the door-frame F on which the improved locking device is rigidly secured. 110

Referring to the specific disclosure of the improved device, it will be seen that it is composed of a pair of substantially duplicate symmetrical sections or members, the inner one 1 of which is stationary and detachably mounted on the door-frame F and the remaining one 2 of which is hinged thereto as indicated at 3 and is adapted to be swung up to the position indicated to enable the bottle 10 B to be engaged or disengaged whichever may be the case. The stationary member 1 is provided with an offset part 4 having openings for the fastenings 5 in one of its walls. These fastenings 5 are adapted to be threaded into the screw-threaded holes formed in the attaching plate 6. This attaching plate is substantially rectangular in shape and is designed to be attached to the door-frame by suitable fastenings 7 which 15 pass through the holes near the opposite ends of the plate. Referring again to the parts of the body, it will be seen that each one is formed at its opposite end with an extension 8 and when the body is in place, 20 these extensions project beyond the ends of the attaching plate so as to prevent persons from removing the fastenings 7. This is an important feature of the invention to be very carefully considered. The extensions 25 8 are recessed as indicated at 9 and when the extensions of the two members are brought together, the recesses serve to constitute housings for the novel locking means to be hereinafter referred to. By carefully 30 examining the particular construction of the bottle-engaging members, it will be seen that they are shaped on their inner sides to conform to the bead of the bottle B and are provided with inturned retaining flanges 35 10 to engage beneath the bead to hold the bottle in place when the members are locked together.

Although some other means could be employed for holding the bottle-engaging members together around the neck of the bottle, 40 I prefer to employ a pivoted latch 11 which is arranged in the recess in one of the end extensions of the movable member 2. This construction can be better seen in Figs. 2 and 5. A stop-pin 12 is located just beneath the latch and serves to limit the downward movement thereof while a flat spring 13 bears on top of the latch and serves to hold it engaged with a slideable locking bolt 55 14 with which the nose 15 thereof is engaged. This locking bolt 14 is slideable through a horizontal bore 16 formed in the stationary bottle-engaging member 1. At its outer end, this slideable locking member 14 60 is beveled as indicated at 17 so as to automatically engage the latch therewith when it is projected through the bore. Also, this bolt 14 is beveled at its inner end as indicated at 18 so that when the milk bottle is 65 placed in position, the bead thereof will en-

gage said beveled end and serve to automatically project this bolt and dispose it in operative position.

It is desirable to normally retain the locking bolt ineffective, that is to have the outer end thereof flush with the bottom of the recess 9 so that when the deliveryman desires to place the bottle in the locking device, the locking means will be ineffective and permit the movable member to be swung up to the dotted line position indicated in Fig. 2. To accomplish this result, the locking bolt is formed between its ends with a longitudinal slot 19 through which a pin 20 extends to limit its sliding movement and a small spring 21 connected to this pin exerts pressure against one end of the slot to normally force the locking bolt inward. It will therefore be seen that the locking means is ineffective until the bottle is placed in position and is then automatically rendered effective.

Although I have shown locking means but at one end of the bottle-engaging members, I desire it to be understood that such means can be employed at both ends in cases where two or more of the locking devices are employed. The locking means at the opposite end would, of course, be a duplicate of that above described and the locking devices would be placed together as shown in Fig. 6 so that one device serves to render the locking means of the other device inaccessible. It often happens that several bottles of milk are left at the same residence and by so constructing the devices as to enable one to render the locking means of the adjoining one inaccessible, as shown, an additional and important feature is brought about. Particular emphasis is to be laid on this additional and novel feature. It is also to be pointed out that by constructing the bottle-engaging members in the manner shown, it is possible to reverse the position of the device so that it will accommodate doors opening to the left or to the right. This arrangement also permits the device to be located on either side of the frame of the closure.

In use, the attaching plate 6 is secured to the door or window-frame adjacent the door or window so that the latter is permitted to co-act with the improved locking device which is in turn bolted or otherwise secured to the attaching plate. When the locking device is secured to the attaching plate, the end thereof in which the novel locking means is arranged is positioned so that when the door is closed, the locking means will be rendered inaccessible. However, by opening the door, the occupant of the house can simply lift the latch 12 to disengage it from the slideable locking member 14 and can then swing the movable bottle-engaging member 2 upwardly to the position shown in the 130

drawing so that the bottle can be removed. As soon as the bottle is removed, the coiled spring which is associated with the locking member will serve to automatically force 5 this member inwardly to dispose the bevelled inner end thereof in position to be engaged by the bottle when the latter is placed therein by the milk deliveryman. This 10 spring also holds the locking member in a position so that the outer end thereof is flush with the bottom of the recess in the extension 8. The bottle-engaging member 2 is then free to be swung upwardly without interference of the slideable locking member. 15 As soon as the bottle is placed in position, the bead thereof engages the bevelled inner end of the locking member and automatically projects the same through the bore and positions it so that when the movable section 20 2 is swung down, the bevelled nose of the latch will engage the bevelled outer end of the locking member and will be automatically engaged with the latter. The house door being closed at this time, the 25 locking means will then be rendered inaccessible to unauthorized persons.

From the foregoing description, it will be seen that I have devised a novel and simple device for locking milk bottles which will 30 prevent unauthorized persons from stealing or removing the bottle after it is placed in position in the device by the deliveryman. The parts of the device are in the form of simple castings which can be manufactured 35 at a comparatively low cost and can be resold to dealers for comparatively small purchase price thus enabling them to furnish the devices free of charge to their consumers. In the end, the dealer will save by 40 using such a device because disputes with the consumers and dealers will be prevented and the dealer will not have to replace the stolen milk as is often the case. With the construction of device shown and described, 45 there is little or no danger of any of the parts becoming disarranged or getting out of order and little time is consumed in engaging and disengaging the milk bottle. Furthermore, the device is applicable to 50 either side of the frame of the closure which is adapted to co-act therewith to render the locking means inaccessible. Other differences of construction distinguishing my device from prior patented and marketed ones 55 used for the same purpose have doubtless been made apparent from the description and drawings and the advantages accomplished by such differences have also been made clear. Moreover, the manner of in- 60 stalling and using the device needs no further description. Therefore, a more lengthy and detailed description is thought unnecessary.

Since probably the best results may be obtained with the construction and arrange- 65

ment herein shown and described, this is taken as the preferred embodiment of the invention. However, I wish it to be understood that minor changes coming within the scope of the invention as claimed may be resorted to if desired.

I claim:

1. A milk bottle locking device comprising a body for attachment to a door or window frame to dispose one end thereof in abutting relation with the door or window, said body including stationary and movable members designed to engage the neck of a bottle, said body having a lock enclosure to be closed by the door or window, and co-acting locking means carried by said members and arranged in said enclosure, being accessible only when the door is opened.

2. A milk bottle locking device comprising a body for attachment to a door or window frame to dispose one end of said body in abutting relation with the door or window, said body being made up of hinged sections having recessed end portions forming a housing, and locking means arranged in said housing for retaining said members in effective engagement with the neck of a bottle, the open side of said housing being closed by the door or window to render the locking means inaccessible when the closure is closed.

3. A milk bottle locking device comprising a body including relatively movable bottle-engaging members having end extensions formed with recesses, a retractile shoulder carried by one of said end extensions, and a pivoted latch carried by the other extension, said shoulder and latch being arranged in said recesses, being 100 designed for co-action with one another, and being rendered inaccessible by a closure as described.

4. The structure set forth in claim 3, said shoulder having a spring associated therewith for normally rendering it ineffective to permit the members to be disengaged from the neck of the bottle, said bottle serving to automatically render said shoulder effective when the bottle is placed in 110 position in the locking device.

5. A milk bottle locking device comprising a body including hinged bottle-engaging members provided with end extensions having recesses formed therein to provide 120 an open-sided lock enclosure adapted to be closed by a movable closure, a slideable locking bolt carried by the stationary bottle-engaging member and a pivoted latch carried by the remaining member, said 125 latch and bolt being adapted for co-action with one another to hold said members together, said locking bolt and latch being located in said recesses and the locking bolt having its inner end bevelled, means for 130

rendering said locking bolt normally ineffective, whereby when said bottle is placed in position, it will coact with said bevelled inner end to automatically project the locking bolt to position it for engagement with said latch.

6. A milk bottle lock comprising a body including hinged bottle-engaging members, a shoulder carried by the stationary member, said shoulder having a beveled outer end portion, and a spring-pressed pivoted latch carried by said movable bottle-engaging member, said latch having a beveled nose to co-act with the beveled end of said shoulder to automatically engage the latch with the shoulder when the movable bottle-engaging member is swung to operative position.

7. A bottle lock comprising an attaching plate adapted to be secured to a stationary support by fastening screws or the like, and a body associated with said attaching plate, said body including relatively movable bottle-engaging members and being of a size to extend beyond the opposite ends of

said attaching plate to prevent the retaining screws of the latter being removed.

8. A bottle lock comprising a pair of locking devices including means for gripping the neck of a bottle and means for rendering said first named means effective, said devices being arranged in abutting relation so that the second named means of each device is rendered inaccessible.

9. A bottle lock comprising a pair of locking devices, each including a body composed of a stationary and a movable bottle-engaging member and each body having a recessed extension, there being locking means for said members located in the recess of said extension, the extensions of the two devices being arranged in abutting relation whereby one body serves to close the open side of the recess of the other body and renders the locking means located therein inaccessible.

In testimony whereof I have hereunto set my hand.

JEROME J. RUEDIGER.
